UNITED STATES PATENT OFFICE.

GUSTAV A. WALSTEAD AND SIVERT MOE, OF CHICAGO, ILLINOIS, ASSIGNEES, BY MESNE ASSIGNMENTS, TO MELVIN C. MOYER, OF CHICAGO, ILLINOIS.

MACHINE FOR MAKING BOOKS.

No. 909,130.

Specification of Letters Patent.

Patented Jan. 5, 1909.

Application filed November 25, 1905. Serial No. 289,126.

To all whom it may concern:

Be it known that we, GUSTAV A. WALSTEAD and SIVERT MOE, citizens of the United States, and residents of the city of Chicago, in the county of Cook and State of Illinois, have invented certain new and useful Improvements in a Machine for Making Books; and we do hereby declare that the following is a full, clear, and exact description of the same, reference being had to the accompanying drawings, and to the letters of reference marked thereon, which form a part of this specification.

This invention relates to a machine for making books.

Heretofore in the construction of cheaper grades of books, such as sales memoranda and many other kinds, and particularly where it is necessary to afford a separable leaf comprising a body portion and a duplicate body portion for each leaf and a stub, it has been customary to print the leaf and cut the same while printing then fold manually or by mechanical means. The leaves are then sorted and arranged by hand and secured in books by stitching after which they are trimmed. The books thus formed are rendered very expensive owing to the number of employees required to do the work and also owing to the relatively slow operation of sorting, binding and trimming by hand.

The object of our improved mechanism therefor is to construct books directly from rolls of paper, each having printing transversely thereon for the entire length of the sheets of which the book is to be formed and each sheet in a roll bearing the same page number or designating character. The number of rolls employed equals the number of leaves required for the book.

The invention embraces, also, the mechanism whereby the sheets are mechanically assembled, fixed and severed from the roll in one continuous operation, dispensing entirely with hand labor and affording a better and much cheaper book than has heretofore been possible.

The invention consists in the matters hereinafter described and more fully pointed out and defined in the appended claims.

In the drawings: Figure 1 is a fragmentary side elevation of a device embodying our invention, showing a part of the same in section. Fig. 2 is a front elevation of the

same. Fig. 3 is an enlarged section taken on line 3—3 of Fig. 1. Fig. 4 is a side elevation of the feeding and cutting mechanism. Fig. 5 is a fragmentary top plan view of the same. Fig. 6 is a section taken on line 6—6 of Fig. 1. Fig. 7 is a section taken on line 7—7 of Fig. 1. Fig. 8 is an enlarged detail of part of the actuating mechanism. Fig. 9 is a top plan view of the stapling mechanism illustrating its relation to the support.

As shown in said drawings: Said mechanism embraces a rack adapted to support any desired number of printed rolls of paper, each of which is appropriated to a different leaf of the book to be constructed and one of which affords the covers. In alinement with said rack and adapted to receive the ends of the printed slips from each roll is a stapling or stitching machine X of any desired kind whereby the strips from said independent rolls are stapled or stitched along one margin of the same and from whence the paper is fed through an automatic feed and cutting machine. The sewed or stapled body composed of all the arranged individual strips is automatically moved forward by said feed mechanism the width of the printed leaf and a transverse strip cut therefrom at each operation of the knife thus forming a book.

Referring first to the supporting rack a portion of which only is shown, A indicates a standard or upright on which is provided a bracket a which receives the ends of the shaft upon which the roll of paper a' adapted to form the cover of the books is supported. Above said cover roll a' bracket arms or supports A' are arranged at an angle on said uprights and journaled thereon are the mandrels a² for the various strips forming the rolls a³ from which the books are to be constructed. Said rolls are journaled on said brackets in such manner as to allow the same to revolve freely as the ends of the strips are fed to the machine and are usually so arranged in the rack that when the ends of the strips forming the separate rolls are brought together the leaves thereon are brought into register. The cover forms the bottom strip and the strip having the highest consecutive page number lies thereon and in a similar manner all the ends of all the various strips are arranged one above the other with the strip appropriated to page 1 forming the top of the book strip or body. If preferred, one or more rolls of impression paper a⁵ may be

likewise secured upon said frame and may be bound with the strips forming the books.

The feed and cutting mechanisms are positioned in advance of the rack and are 5 adapted to receive the arranged sheets from said rolls which are supported upon an upright frame comprising the legs B, B', side frame members b—b' and end frame members b²—b³ which may be constructed in any desired manner and of any suitable material. 10 The top or bed of said frame comprises a plurality of relatively thin bars B² which are pivotally engaged at their front ends on the front end member b² as shown in Fig. 1 and 15 extend rearwardly and are supported near their rear ends upon the end member b³ as shown in Fig. 1 and afford a support which offers but slight resistance to the forward movement of the body strip.

20 At the front or cutting end of the machine is provided a vertically reciprocating adjustable knife C and a presser foot D adapted to hold the paper during the cutting operation. Said knife C is rigidly secured upon a knife-carrying frame C' of suitable construction adapted to reciprocate vertically and laterally in guides afforded at the front end of the machine comprising uprights B³ which extend above the front end frame member or table b² in alinement with the outer face of the legs B' against which said knife and knife frame C' slide. Said knife and frame are held in place by bars c which are bolted at their ends to the face of said upright B³ and 35 said legs B' as shown in Fig. 4 and are offset therefrom a sufficient distance to form a guideway for said frame. Said knife frame C' as shown comprises a casting provided with a broad horizontal slot therein of 40 greater length than the width of the frame and through which the table b² projects. As shown a strip of wood b⁴ or other suitable material is set in said table to afford a base for the operation of said knife.

45 The knife frame C' as shown more clearly in Fig. 2 is provided adjacent each lower corner with a downwardly and laterally inclined guide slot c' which incline in the same direction and through each of which extends a 50 guide bolt or pin c² which is rigidly engaged in said legs B' and bars c and provided with anti-friction rollers c⁵ shown in dotted lines.

The presser foot D is carried upon a vertically movable bar d having sliding engagement in suitable grooves in the inner faces of the uprights B³ whereby it may move upwardly and downwardly with the knife but is prevented from lateral movement. For this purpose as shown said bar is actuated 55 from the knife frame C' which is provided on its rear side with rearwardly directed pins d' which project into slots d² in said bar d. Said slots as shown in dotted lines in Fig. 2 60 extend horizontally and at the ends corresponding with the downwardly inclined por-

tions of the slots c' are slightly inclined downwardly. The pins d' are provided with anti-friction rollers d³ which engage in said slots d² so that as the knife frame moves downwardly the presser foot D is carried therewith and forced into firm engagement with the body strip and owing to the inclination of said slots d² the presser foot remains in engagement with the strip until the knife is raised clear thereof.

75 For the purpose of operating the knife C and the presser foot D a shaft E is journaled in the end frame members and is provided on its forward end with a crank arm e having on the end thereof a block c⁴ adapted to engage in a vertical guide slot c³ in said knife frame whereby, as said crank is rotated, the frame is caused to move laterally and vertically upon the pins c² thereby raising and lowering the presser foot D. Rigidly engaged on the shaft E is a beveled gear e' adapted to mesh with a beveled gear e² carried on the inner end of the shaft E' journaled in a bearing sleeve b⁶ which is carried on the side frame member b'. On the outer 90 end of said shaft E' is rigidly engaged a gear e³ which intermeshes with a pinion e⁴ upon the drive shaft E² journaled in suitable bearings in the side frame members and provided with a drive wheel e⁵.

95 Means are provided for engaging the book or body strip intermediate the stapler or stitcher and the cutting mechanism and acting to intermittently feed the same forwardly beneath the knife a distance equal to the 100 width of the books and for this purpose said feed mechanism as shown is slidably upon ways which consist of horizontal, parallel rods F of any suitable kind secured in lugs f upon the side frame members at a suitable 105 height. As shown said feed mechanism comprises a carriage or table G having downwardly directed apertured legs g thereon which slidably engage said ways and at its forward end is provided with upwardly directed standards or arms g' which are situated on the outer sides of the bars B². Said standards g' are provided with forwardly directed apertured ends in which and in lugs g² on the front end of said table are engaged 110 the vertically disposed guide rods or ways g³. Slidably engaged on said guide rods by means of integral apertured lugs g⁴ is the upper gripping jaw G', comprising as shown a transverse head g⁵ which is provided with 115 downwardly and inwardly directed arms g⁶ having slots g⁷ in their inwardly directed ends which extend horizontally and downwardly in the same direction, as shown in Fig. 6. Slidably engaged in said slots g⁷ by 120 means of pins g⁸ carried thereon is the cam yoke H having a central aperture therein through which the shaft E extends. Said yoke H as shown is supported in position by 125 means of levers J—J which are pivoted at 130

their centers upon the forward end of the table and at their lower ends are pivoted on the pins g^8 .

Extending inwardly from the lateral margins of said aperture are the cam tits h and h' adapted to be engaged by the cam H' which is rigidly engaged upon the shaft E and of a length approximately equal to the travel of the table G . Said cam as shown is provided with a longitudinal rib h^2 adapted to contact with said cam tits h and h' and shift the yoke laterally and owing to the inclination of the slots g^7 acts also to move the jaw G' vertically on the guide rods g^3 . Adjustably engaged upon the head g^5 is the contact plate or bar G^2 which as shown is slotted to permit its being adjusted as to height with respect to the bars B^2 to admit varying thicknesses of book or body strips to pass below it.

The lower gripping jaw I comprises a transverse bar provided with broad faced lugs or teeth i which project upwardly between the bars B^2 and are approximately flush with the tops thereof. As shown said jaw I is also slidably engaged upon the guide rods g^3 by means of apertured lugs i^2 and is provided with horizontal slots in the ends thereof in which are slidably engaged pins i^3 carried in the upper ends of the levers $J-J$ and by means of which said jaw is raised and lowered when the yoke is operated. Coiled springs i^4 are carried on the rods g^3 and engage at one end on the lugs g^2 and at the other ends on the lugs i^2 and act to normally hold the jaw I at the upper limit of its movement.

The feed table G is adapted to reciprocate longitudinally of the machine and to feed the book or body strip forwardly the width of the book at each forward movement. For this purpose a transverse shaft K is journaled in the side frame members and rigidly engaged thereon is a lever K' , one arm of which extends upwardly between the ways F and a bar k is pivoted thereon and on the table G and acts when said lever is operated to move the table backwards and forwards. Connected in the lower end of said lever K' is a rod k' which extends forwardly and as shown a coiled spring k^2 is engaged in the end thereof and to the front frame member of the machine and acts normally to hold the feed table at the rearward limit of its movement. Said shaft K projects beyond the side of the frame member b' and has rigidly engaged on the end thereof an upwardly extending lever K^2 , on the upper end of which is pivoted a bar K^3 provided with a slotted forward end k^3 through which extends said shaft E' . A cam K^4 having a relatively broad end thereon is rigidly engaged on said shaft E' adjacent the bar K^3 and is adapted to engage an anti-friction roller k^4 on the end k^3 of said bar and move

said bar forwardly thereby rotating the shaft K and moving the feed table G forwardly.

The stapler or stitcher A^2 which may be of any usual or preferred construction adapted to secure the stub portions of the leaves together is situated at the rear of the machine in position to operate upon the book strip as it comes from the rolls. A roller b^5 is journaled upon the rear ends of the bars B^2 which acts to hold the sheets from said rolls a' and a^2 in close contact. Means are provided for operating said stapler or stitcher while the book strip is at rest or stationary comprising a shaft L journaled in suitable bearings l , adjacent the base of the stitcher on which is a laterally directed arm l' which rests at its outer end on the pedal L' of the stitcher. On the end of said shaft at the rear of the machine is rigidly engaged an arm L^2 the upper end of which normally lies close to the side of the shaft E which is provided with a cam l^2 adapted to throw said lever in a direction to depress the pedal L' and operate the stitcher.

The operation of our device is as follows: The leaf rolls a^2 and cover roll a' are arranged upon the rack at the rear of the machine and the strips therefrom forming the body strip for the book are brought forward in such order that the identification characters or page numbers will read consecutively in the books. Said body strip is passed beneath the roller b^5 to the feed mechanism and lies upon the bars B^2 and is so adjusted that as it is moved forwardly the knife C will cut the strip at the proper points to detach the completed books.

The mechanism is so timed that when the knife C is raised the feed carriage will move the strip forwardly the width of a book. As said feed carriage is about to begin its onward movement the cam follower H' on the shaft E contacts with the cam tit h' on the cam yoke H throwing said yoke laterally in the direction of the upward inclination of the slots g^7 thereby drawing the jaw G' downwardly into engagement with the strip. At the same time the movement of the yoke H throws the levers J into vertical position thereby bringing the jaw I into binding engagement with the under side of the strip and holding it firmly against the jaw G' . The cam K^4 on the shaft E' now begins to operate the levers K' and K^2 to move the carriage forwardly to the position shown in Figs. 1 and 4 and owing to the shape of said cam, and the fact that the shafts E and E' are geared to rotate at the same speed, said carriage is moved forwardly during approximately one quarter of a revolution of the shaft E and reaches the forward limit of its movement just as the knife C is about to descend. Owing to the relatively broad end on said cam the carriage is held stationary at its forward limit long enough for the knife

and presser foot D to engage the strip and for the cam follower H' to engage the cam tip h and open the jaws preparatory to the return movement of said carriage.

5 The crank arm e on the shaft E operates the knife frame C' raising and lowering it with each revolution of said shaft. Owing to the inclination of the slots c' the knife C is forced through the strip with a lateral and downward movement to its downward limit as shown more clearly in Figs. 1 and 2. While the knife moves laterally the presser foot, which is connected with the knife frame by means of the pins d' extending into the horizontal 10 slots in the bar d, is permitted only vertical movement in the ways B³ and is brought downward by said frame into binding engagement with the strip. Inasmuch as the slots d² are inclined at one end complementally with the slots c', when the knife begins 15 its upward movement said presser foot is retained in engagement with the strip and is not elevated until the knife is practically clear of said strip.

25 The cam l² is so positioned on the shaft E that it operates the stitching machine while the body strip is at rest thereby securing the leaves together preparatory to the severance of the books.

30 Obviously many details of construction may be varied without departing from the principles of our invention.

We claim as our invention:

1. In a device of the class described the 35 combination with means supporting a plurality of rolls of paper of means for stitching the strips therefrom together along one margin, automatically operated means severing the same equal distances apart, and 40 means feeding the strips forward to the severing means including oppositely movable automatically operated jaws adapted to engage the strips therebetween prior to each forward movement of the feeding means.

45 2. A device of the class described comprising a roll supporting rack, a stitching mechanism, a frame in advance thereof, a plurality of horizontal thin bars pivoted thereto, a carriage movable beneath said 50 bars, simultaneously movable gripping jaws, one of which is provided with a plurality of teeth extending between said bars, a cam, means operated thereby, moving said carriage forwardly, means simultaneously moving 55 said jaws to gripping position, a vertical, laterally movable knife and mechanism for operating the same.

3. In a device of the class described the 60 combination with a rack for supporting a plurality of strips arranged in rolls, of means for stitching said strips together adjacent one margin, reciprocating means for intermittently feeding said strips forwardly and means for severing said strips at regular intervals.

65 4. In a device of the class described the

combination with means for supporting a plurality of strips, of means for stitching said strips together adjacent one margin, horizontally movable means adapted to feed said sheets forwardly, including simultaneously 70 movable means adapted to engage the strips prior to a forward movement thereof and adjustable means severing said strips.

5. In a device of the class described the combination with a bed for supporting strips, 75 of means for stapling said strips together adjacent one margin, a carriage adjacent the bed, standards on said carriage, a guide engaged to each standard, simultaneously and oppositely movable gripping jaws carried on 80 said guides and an adjustable cutting knife.

6. In an automatic book-making machine the combination with means for supporting a plurality of rolls of paper, means adapted to secure the strips of paper from the rolls 85 along one margin, means adapted to intermittently feed the paper forwardly and adjustable cutting means adapted to sever the complete books.

7. In an automatic machine for making 90 books the combination with means for supporting a plurality of rolls of paper of stitching, means adapted to bind the strips of paper from said rolls together, a reciprocating feeder adapted to intermittently feed the 95 strips forwardly, power-operated means for moving the feeder forwardly, flexible means for returning the feeder to normal position and a laterally movable adjustable knife adapted to sever the strips.

100 8. In a device of the class described the combination with a frame of stitching mechanism, a reciprocating knife in said frame, a feed carriage, automatically operated relatively adjustable upper and lower gripping 105 jaws on said carriage, arms secured to the upper jaw, said arms and lower gripping jaw provided with slots, pivoted levers movable with the carriage, means secured to the levers engaging in the slots whereby movement of one jaw simultaneously actuates the other jaw, means connected to actuate one of the jaws at each limit of movement of the carriage and means adapted to intermittently move said carriage towards and from the 110 knife.

9. In a device of the class described the combination with stitching mechanism and a frame of a reciprocating knife on said frame, a strip of soft material below said 115 knife adapted to receive the edge thereof, horizontal ways on said frame, a carriage movably engaged thereon, gripping jaws on said carriage, means adapted to automatically operate one of said jaws, means connecting 120 the jaws whereby movement of the automatically operated jaw adjusts the other jaw into gripping relation therewith and means for intermittently moving said carriage to- 125 wards and from the knife.

10. In a device of the class described the combination with a frame of a reciprocating knife thereon, means for stitching sheets together along one margin, parallel, horizontal ways on said frame, a feed carriage movable thereon, upper and lower jaws on said carriage, automatic means adapted to open and close said jaws respectively at the forward and rearward limit of movement of the carriage and means adapted to intermittently operate said carriage. 70
11. In a device of the class described the combination with a frame of cutting mechanism carried thereon, stapling means at the rear of said frame, a feed carriage adapted to alternately move toward and from the cutting mechanism, oppositely movable jaws thereon, one of which is adjustable for making books of different thicknesses, means connecting said jaws, a shaft, means thereon adapted to open and close said jaws and a crank on said shaft adapted to actuate the cutting mechanism vertically and laterally. 80
12. In a device of the class described the combination with a frame, a longitudinally slotted bed thereon, means adapted to secure sheets together along one margin, a feed carriage movable beneath said bed, upper and lower jaws thereon adapted to engage the strip therebetween and automatic means adapted to release said jaws when the carriage reaches its forward limit. 85
13. In a device of the class described a frame, a stapling device at the rear thereof, a plurality of longitudinal bars on said frame, a reciprocating carriage beneath said bars, a pair of vertically movable jaws on said carriage, operating mechanism for said jaws including a yoke carried on the carriage and means adapted to shift said yoke laterally to open and close said jaws. 100
14. In a device of the class described the combination with a frame of a plurality of longitudinal bars thereon, a reciprocating carriage beneath said bars, vertically and oppositely movable gripping means thereon, means adapted to open and close the gripping means, means adapted to reciprocate the carriage, cutting means carried on said frame and means adapted to stitch or staple sheets along one margin prior to engagement by said gripping means. 110
15. In a device of the class described the combination with a frame, of a plurality of bars supported thereby forming a bed, a carriage movable beneath said bed, pivotally supported levers carried thereby, vertically movable jaws pivoted on said levers, a yoke engaged on said levers, means acting to shift said yoke laterally to open and close said jaws, means adapted to stitch sheets together prior to engagement by said jaws and means severing the sheets. 120
16. In a device of the class described the combination with a frame of a stapling de- 130
- vice, a knife carried by said frame, a longitudinally movable carriage on said frame, vertically movable gripping jaws on said carriage, a feed bed comprising a plurality of longitudinal bars extending between said jaws, a yoke operatively connected with said jaws and means adapted to shift said yoke laterally and open and close the jaws. 70
17. In a device of the class described the combination with a frame of reciprocating cutting means thereon, a stapling machine adapted to fasten strips together, longitudinal ways on said frame, a reciprocating feed carriage thereon, vertically movable, longitudinally slotted jaws on said carriage, levers pivoted on the carriage engaging in the slots in said jaws, a yoke pivotally engaged on said levers, a shaft extending therethrough and a cam thereon adapted to shift said yoke laterally. 80
18. In a device of the class described the combination with a frame of a vertically and laterally movable knife thereon, a stapling device at the rear of said frame, a carriage on said frame, means for moving said carriage to and from the knife, vertically and oppositely movable gripping jaws on said carriage, a plurality of bars extending between said jaws forming a bed adapted to support strips, a shaft, a yoke operated thereby and levers operatively connected with both jaws and actuated by said yoke, acting to close the jaws on the strip at the rearward limit of movement of the carriage and to open the jaws at the forward limit thereof. 90
19. In a device of the class described the combination with a stapling device of a frame adjacent the same, a longitudinal shaft journaled therein, a vertically and laterally movable knife operated by said shaft, a pair of longitudinal ways, a feed carriage movable thereon, a transverse shaft adapted to drive said longitudinal shaft, a cam thereon and means operated by said cam acting to reciprocate said carriage. 105
20. In a device of the class described the combination with a stapling or stitching machine of a frame, vertical ways on said frame, a knife frame, a knife adjustably secured thereto, means for actuating the knife frame to move the knife to and from cutting position, a presser foot operated by movement of the knife frame to engage the sheets and remain lowered until after the knife has severed the sheets and a feed mechanism adapted to feed the material to the knife. 115
21. In a device of the class described the combination with stapling or stitching means of a frame positioned in advance of the same, a shaft journaled in said frame, vertical ways on said frame, rollers journaled in said ways, a knife frame in said ways and provided with slots in which said rollers engage, a knife secured to said frame, means on 125

said shaft adapted to operate said knife, mechanism adapted to feed material beneath the knife, including oppositely movable gripping jaws, rocking mechanism connected therewith for moving the same and means for rocking said mechanism thereby moving the jaws.

22. In a device of the class described the combination with a stitching or stapling device of a frame in advance of the same, vertical ways thereon, a knife frame in said ways and provided with laterally and downwardly inclined slots, rollers journaled in said ways and engaging in said slots, a knife on said frame, means movably engaged on said frame adapted to engage the material operated upon, means for operating said knife frame, an automatically operated feed carriage adapted to feed material beneath the knife, including gripping jaws adapted to engage the material and oscillating mechanism for moving the jaws.

23. In a device of the class described the combination with a book stitching machine of a frame, a plurality of bars pivoted at one end to the frame and forming a support, a carriage movable longitudinally of the bars, oppositely movable coacting gripping jaws, one jaw having teeth extending between the bars, vertical ways secured to the frame, a knife frame carried in said ways, a knife thereon, means adapted to move said frame inclined to the vertical, a vertically movable presser foot, means operatively connecting said knife frame and foot whereby said foot remains stationary during part of the upward movement of the frame and means for operating said frame and foot.

24. In a device of the class described the combination with a stitching machine of means for supporting material, a frame, a shaft journaled therein, vertical ways on the forward end of said frame, a knife frame carried in said ways and provided with slots therein at an inclination to the perpendicular, anti-friction rollers journaled in said ways and engaging in said slots, a knife in said frame adapted to sever material, a presser foot slideable in said ways and provided with horizontally and downwardly directed slots, anti-friction rollers journaled on said frame and engaged in said slots adapted to depress the presser foot and hold the same depressed until after the knife has severed the material, a crank arm on said shaft engaged in a vertical slot in said frame and a reciprocating feed mechanism adapted to feed material beneath the knife when the latter is raised.

25. A book making machine comprising means for stitching sheets together, a frame, a plurality of bars pivoted at one end to the front of said frame and supported thereon at the rear end thereof, simultaneously movable gripping jaws adapted to engage the books therebetween, an oscillating yoke adapted

to actuate said jaws, means moving said jaws forwardly when in gripping position and an adjustable knife adapted to sever the sheets.

26. A book making machine comprising a frame, a bed supported thereby, stitching mechanism adjacent the rear of said bed, gripping jaws on opposite sides of said bed, means adapted to simultaneously move said jaws oppositely, a carriage carrying said jaws, a cam, mechanism operated thereby to move said carriage forwardly, a knife and mechanism for automatically lowering the same to sever material.

27. A book making machine comprising a frame, a bed supported thereby, a stapling mechanism adapted to fasten a plurality of sheets together adjacent one margin, a horizontal way on each side of the frame, a carriage movable thereon, gripping jaws carried by said carriage, oscillating means adapted to actuate said gripping jaws, means moving said carriage forwardly and rearwardly, a vertically movable presser foot, means lowering the same as the carriage reaches its forward limit of movement and a knife adapted to cut the sheets.

28. In a book making machine the combination with a stapling mechanism of a frame in advance of the same, a plurality of bars engaged at one end to said frame and supported at their opposite end by the frame, a carriage movable longitudinally of said bars, means movable with the carriage adapted to engage sheets, oscillating mechanism adapted to actuate said means, a knife frame, a knife carried thereby and rotary means adapted to depress and elevate the knife frame.

29. In a device of the class described the combination with a frame of a plurality of horizontal bars supported thereby, a stapling mechanism supported above the rear of said bars, gripping jaws, one above the bars and one beneath the same having teeth projecting between the bars, automatic means simultaneously moving said jaws oppositely, a cam, means actuated thereby for moving the jaws forwardly when in gripping relation, a knife bar, a knife carried thereby and a presser foot actuated by movement of said knife bar.

30. In a device of the class described the combination with a frame of a plurality of bars supported thereby, a stapling device adjacent the rear of said frame, a feed mechanism movable longitudinally of said bars, including simultaneously movable jaws, a vertical way on each side of the frame, rollers therein, a slotted knife bar one slot for each of said rollers, a knife carried by said bar, a slotted vertically movable bar, a presser foot carried thereby, rollers carried by said knife bar, one engaged in each slot in said bar and means actuating the

knife bar thereby simultaneously actuating the knife and presser foot.

31. In a device of the class described the combination with a frame of a bed supported thereby, a stapling machine at the rear of the frame, a feed carriage, gripping means carried thereby, a slotted knife bar, an adjustable knife carried thereby, a presser foot actuated by the knife bar, a shaft, a crank thereon and means carried on the crank and engaged in the slot of said knife bar adapted to actuate the same.

32. In a device of the class described the combination with a frame of a plurality of bars supported thereby, a feeding carriage, stapling means at the rear of said carriage, a knife frame having a slot therein, a knife carried thereby, a presser actuated approximately simultaneously with said knife, a crank and a reciprocating block engaged thereto and movable in said slot.

33. In a device of the class described the combination with a roll supporting rack having rolls thereon, of means supporting the strips horizontally from all of said rolls, a stapling device adapted to fasten said strips along one margin, means adjacent the support for feeding the strips, said means including gripping jaws thereon, one above and one below the strips, means moving said jaws to grip the strips at one limit of movement of said movable means, means adapted to release the jaws at the opposite limit of movement thereof and a knife adapted to sever said strips from the rolls.

34. In a device of the class described the combination with a roll supporting rack having rolls thereon, of means supporting the strips horizontally from the rolls, means securing the strips together along one margin, a carriage adjacent said support, oppositely movable jaws thereon, means forcing said jaws into engagement with opposite sides of the strips prior to moving the same forward, means firmly holding the strips at the end of the forward movement, a knife adapted to cut the strips, and said means for forcing the jaws to engage the strips adapted to release the jaws from said strips prior to a return movement thereof.

35. In a device of the class described the combination with a frame adapted to support a plurality of rolls of paper, of a stapling device in advance thereof, means supporting the strips of paper as unwound from said rolls, a carriage adjacent the support, jaws on the carriage adjustable relatively to each other and adapted to firmly engage the strips therebetween, levers connecting the jaws, means actuating one jaw adapting the levers to simultaneously move the other

jaw into gripping engagement, means moving the carriage forward when said jaws are in gripping engagement, means firmly pressing the strips together when the carriage reaches the forward limit of movement and an adjustable knife adjacent thereto adapted to sever said strips.

36. In a device of the class described the combination with a frame adapted to support a plurality of rolls of paper, of means binding one margin of said paper, a bed adapted to support said bound strips, a carriage movable relatively of the bed, means on the carriage adapted to grip the strips, said means moved forward by the carriage a predetermined distance, means for moving the carriage forward, means pressing the forward ends of said strips into close relation at the end of said forward movement, a knife severing said strips and means returning the carriage to normal position prior to another forward movement and severing of the strips.

37. In a machine of the class described the combination with a rack having rolls of paper supported thereby, of a stapling machine in advance thereof, a frame adjacent thereto, a shaft journaled longitudinally of said frame, a driving shaft, intermeshing gears on said shafts, a carriage actuated by the driving shaft, jaws thereon adapted to grip the strips from said rolls prior to a forward movement of the carriage, a knife actuated by the longitudinal shaft to sever said strips and means operatively connected with said longitudinal shaft to operate said stapling machine.

38. In a device of the class described the combination with a roll supporting rack having rolls of paper supported thereon, a frame, a bed supported by the frame comprising a plurality of bars adapted to support the strips from said rolls, a stapling machine intermediate the rolls and frame, movable means engaging said strips and moving the strips during its movement in one direction and movable relatively to the strips during the return movement, means for cutting the strips, a driven shaft actuating said means and means operatively connected with the driven shaft adapted to operate said stapling machine when said strips are at rest.

In testimony whereof we have hereunto subscribed our names in the presence of two subscribing witnesses.

GUSTAV A. WALSTEAD.
SIVERT MOE.
